UNITED STATES PATENT OFFICE

153,164

DESIGN FOR A FISH LURE

David J. Neukom, Webb Lake, Wis., assignor, by mesne assignments, of one-half to George Neukom, Chicago, Ill.

Application April 30, 1947, Serial No. 138,711

Term of patent 14 years

(Cl. D31—4)

To all whom it may concern:

Be it known that I, David J. Neukom, a citizen of the United States, residing at Webb Lake, in the county of Burnett and State of Wisconsin, have invented a new, original, and ornamental Design for a Fish Lure, of which the following is a specification, reference being had to the accompanying drawings, forming a part thereof.

In the drawings:

Fig. 1 is a plan view of a fish lure, showing my new design; and

Fig. 2 is a side elevational view thereof.

I claim:

The ornamental design for a fish lure as shown.

DAVID J. NEUKOM.
